PICTURE FRAME SUPPORT

Filed Sept. 15, 1930

UNITED STATES PATENT OFFICE

CLAUDE E. HAINES, OF TACOMA, WASHINGTON

PICTURE FRAME SUPPORT

Application filed September 15, 1930. Serial No. 482,048.

This invention appertains to new and useful improvements in picture frame supports, and more particularly to novel supporting means which can be converted from the wall type to a table supported type.

5 The principal object of this invention is to provide a picture frame provided with supporting means which will permit the picture to be placed on supporting surfaces of very limited area.

10 Other important objects and advantages of the invention will readily become apparent to the reader of the following specification.

15 In the drawings:

Figure 1 represents a side elevational view of the device.

Figure 2 represents a rear elevational view of the device shown in Figure 1.

20 Figure 3 represents a side elevational view of a slightly modified form of the invention.

Figure 4 represents a rear elevational view of the structure shown in Figure 3.

25 Figure 5 represents a perspective view showing the rear side of the third form of the invention.

Figure 6 represents a perspective view looking at the curved side of a circular picture frame, employing the same supporting means shown in Figure 5.

30 Figure 7 is a rear elevational view showing the rear side of the picture frame shown in Figure 5 with the legs removed and replaced by wall suspension means.

35 Referring to the drawings wherein like numerals designate like parts, it can be seen in Figure 1 that numeral 5 represents a picture frame, which is shown in Figure 2, as being of rectangular shape and provided

40 with an apertured ear 6 at its rear side and adjacent the upper edge thereof. A pair of vertically spaced barrels 7-7 are provided on the back side of the frame 5, in aligned position. A triangular shaped leg structure 8 is provided with a pair of upwardly extending pintles 9 on one side edge portion thereof.

45 These pintles are engageable through the barrels 7-7 in the manner shown in Figure 1, so that when the lower edge of the picture frame and the lower end of the leg 8 are

brought to rest upon a supporting surface, the picture frame may be maintained supported in the inclined position shown in Figure 1.

5 As is shown in Figures 3 and 4, the frame is still denoted by numeral 5, as is the leg structure 8. However, the barrels 7-7 in Figures 1 and 2 are denoted by numeral 7'-7' and each of these barrels may be constructed by bending the intermediate portion of the strip at 10, to form a loop, with the end portions of the strip disposed against the inner side of the back section of the picture frame to anchor the barrel in position.

65 To permit the picture frame 5 in Figures 3 and 4 to be supported by a driven element, in a wall, an eye member 11, provided with an aperture 12 therein is also provided with a depending portion 13, in which a slot is 70 located for receiving the upper barrel 7'. Obviously, by removing the leg structure 8, and inserting a pin through the upper barrel 7' as shown in Figure 7, the member 11 can be used in cooperation with a projection 75 on a wall to support the picture frame.

75 Figures 5 and 6 employ the same barrel construction and leg construction disclosed in Figures 3 and 4, excepting that the picture frames 5', disclosed in Figures 5 and 6 80 are of different shape, from that disclosed in Figures 1 to 4 inclusive, so as to call for a pair of the leg structures and the corresponding increase in the number of barrels.

Figure 7 discloses the same form of picture frame shown in Figure 5, with the ear members 11 interconnected by a strand 14, which is engaged below the projection driven into the wall.

85 While the foregoing specification discloses the invention in specific terms, it is to be understood that numerous changes in the shape, size, and materials can be resorted to, without departing from the spirit of the invention or the scope of the appended claims.

90 What is claimed is:

1. A picture frame, comprising a back section, an apertured projection on the back side of the section, an apertured plate, said plate being provided with an additional 100

opening therein for receiving the apertured projection, so that the apertured projection will project through and beyond the said plate, and a pin for disposition through the 5 apertured projection.

2. In combination, a picture back, an aperture projection on the picture back, a plate having an aperture therein for receiving a hanger, said plate being provided with an 10 additional opening for receiving the aperture projection, a leg, said leg being provided with a pintle for disposition through the aperture projection whereby the leg is swingably secured to the picture back and 15 the plate is secured on the aperture projection against displacement.

In testimony whereof I affix my signature.

CLAUDE E. HAINES.
